US0D1096509S

(12) **United States Design Patent** (10) **Patent No.:** **US D1,096,509 S**
(45) **Date of Patent:** **** Oct. 7, 2025**

(54) **BUCKLE**

(71) Applicant: **Fidlock GmbH**, Hannover (DE)
(72) Inventor: **Timon Oliver Pankoke**, Hannover (DE)
(73) Assignee: **FIDLOCK GMBH**, Hannover (DE)

(**) Term: **15 Years**

(21) Appl. No.: **29/869,419**

(22) Filed: **Dec. 30, 2022**

(30) **Foreign Application Priority Data**

Jul. 7, 2022 (DE) 402022100534.2

(57) **CLAIM**

The ornamental design for a buckle as shown and described.

DESCRIPTION

FIG. 1 is a top, rear, left side perspective view of a buckle, showing the new design;

FIG. 2 is a top plan view thereof;

FIG. 3 is a rear view thereof;

FIG. 4 is a front view thereof;

FIG. 5 is a right side view thereof; and,

FIG. 6 is a left side view thereof.

Broken lines depict portions of the buckle that form no part of the claimed design.

1 Claim, 6 Drawing Sheets
